CIGARETTE PACKAGE

William V. Richner, Champaign, Ill., assignor of one-half to James F. Heffernan, William J. Heffernan, Mary E. Heffernan, and Stanley E. Workman, doing business as J. Heffernan and Son, Champaign, Ill., a partnership

Application October 7, 1954, Serial No. 460,801

4 Claims. (Cl. 131—257)

The invention relates generally to cigarette packages and more particularly to a package provided with a holder for holding a lighted cigarette.

The general object of the invention is to provide a cigarette package having novel means for holding a cigarette in such a manner that the cigarette is firmly held and cannot fall or roll away from the package.

Another important object is to provide a cigarette package having novel means for holding a lighted cigarette by which the lighted end of the cigarette is held spaced from the package so that it cannot burn the package.

A further object is to provide a cigarette package having novel means for holding a cigarette which will hold the cigarette firmly but will not tear the paper covering of the cigarette.

Still another object is to provide a cigarette package having novel means for holding a cigarette which may be enclosed in a standard form of package and becomes available for use on opening the package in the usual manner.

Other objects and advantages will become apparent from the following description taken in connection with the accompanying drawing, in which:

Fig. 1 is a perspective view of a cigarette package embodying the features of the invention and having a cigarette holder with a lighted cigarette positioned therein;

Fig. 2 is a top or end view of the cigarette package shown in Fig. 1 with the holder in position for use;

Fig. 3 is a fragmentary perspective view of one of the layers or wrappers of the wrapping for the package and showing the holder secured thereto;

Fig. 4 is a fragmentary perspective view of the cigarette package when closed;

Fig. 5 is a fragmentary perspective view of the cigarette package when partially opened; and

Fig. 6 is a fragmentary perspective view of another form of cigarette package.

The invention is adapted for use with a cigarette package of the type comprising a multi-layer wrapping enclosing a plurality of cigarettes, the wrapping being made of flexible sheet material. In this form of package there is incorporated a holder for holding either a lighted or unlighted cigarette and which becomes accessible for use when the package is opened in the usual manner as by tearing off a portion of the wrapping at one end of the package.

The wrapping for a package of this character usually comprises a liner in the form of a sheet of paper having a metallic foil covering. Such liner is wrapped around a plurality of cigarettes, usually twenty, and is of a width sufficient to extend beyond the ends of the cigarettes. The package is molded into a rectilinear form, and the extending portions of the liner are folded over the ends of the cigarettes to completely close them. Thus in Fig. 3

2

I have shown a fragmentary portion of such a liner, indicated at 10, before being wrapped about the cigarettes. With such a liner, the extending portion thereof, at that end of the package which is to be opened and which is usually referred to as the top, is first folded in at the sides of the package, as indicated at 11, and then the portions extending beyond the faces of the package are folded in to provide an underlap 12 and an overlap 13. The extension of the lining beyond the ends of the package is sufficient so that the portion 13 overlaps or covers a part of the portion 12 and both portions 12 and 13 overlap parts of portions 11, as their names indicate.

Enclosing the liner is another layer, indicated at 14, constituting a covering jacket for the liner. Such jacket is usually of paper and is printed on its exterior surface to show the trademark for the cigarettes and other data. The layer 14 is wrapped around the liner 10 in the same manner as the latter is wrapped around the cigarettes and is of such width that one edge thereof lies at or adjacent the upper end of the package, as indicated at 15 in Fig. 1. The opposite edge extends beyond the other end of the package and is folded, as indicated at 16, in the same manner as the liner is folded at the ends of the package, to provide a complete closure for that end of the package. The package is held closed by a revenue stamp 17 which overlies the folded portions 12 and 13 of the liner 10 intermediate the sides of the package to leave parts of folded portions 11, 12 and 13 exposed. The ends of the stamp 17 extend down onto the covering jacket 14, the stamp throughout its area being glued to the package. The package may also have an outer transparent sealing jacket usually made from a sheet of cellophane or the like and which will be more fully described in connection with the description of Fig. 6 of the drawing.

A smoker frequently wishes to lay down his cigarette while it is lighted. When no ash tray is immediately available, he can lay it on some form of ledge with the lighted end protruding beyond such ledge. If the ledge is provided by an article of furniture and the smoker forgets the fact that the cigarette is gradually burning shorter, it is apt to burn so far as to have the burning portion reach the article of furniture and produce an unsightly burn or scar thereon. Moreover, there is nothing to keep the cigarette from rolling away, if the ledge is not absolutely level, and it is apt to fall on the floor.

If the smoker uses his package of cigarettes as a ledge, such package is not always in a perfectly flat condition and the burning cigarette may roll off of the package onto some surface where it would cause damage. Moreover, even if it did not roll off, if it were permitted to burn too long in one position, the burning end would reach the cellophane wrapping and set fire thereto.

As hereinbefore mentioned, the holder is adapted to be incorporated in a cigarette package of the type described above. It comprises a strip of relatively stiff material, indicated generally at 20 in Fig. 3, having one end portion 21 adapted to be secured within the package in a manner hereinafter described, and the other end portion, indicated at 22, formed to receive and hold a cigarette. The portion 22 is provided with a notch 23 in which the cigarette may be inserted. The strip 20 is bent, when in use, so that the portion 22 thereof is parallel to the end surface of the package and extends substantially perpendicularly to one face of the package, as indicated in Figs. 1 and 2. A lit cigarette may then be placed in the holder, as shown in Fig. 1, with a portion of the cigarette adjacent the lighted end thereof inserted within the

notch 23 and the other end of the cigarette lying on the face of the package. Thus the cigarette will be held firmly in position and cannot roll off the package.

The holder is also arranged, to extinguish the cigarette should it be permitted to burn to a point approaching the holder. To accomplish this result, the notch 23 has a width slightly less than the normal diameter of the cigarette so that a slight pinching effect is produced when the cigarette is inserted in the notch 23. The pinching effect causes a compacting of the filling of the cigarette to reduce the possibility of air flow through the filling at the point where it is gripped by the holder. As a result of such compacting, the burning will be extinguished as it approaches the compacted portion because of lack of sufficient oxygen to support combustion of the filling. The pinching action of the notch 23 is enhanced by forming the lower end thereof in a semi-circle, as indicated at 24, so that not only is the cigarette gripped at its sides by the margins of the notch 23, but it is also gripped around its lower portion by the semi-circular portion 24 to assist in the compacting action when the cigarette is pushed down within the notch.

While the notch 23 effects a slight pinching action on the cigarette, it is so formed that the paper of the cigarette will not be torn as it is being inserted into the notch. To this end, corners formed by the outer end edge of the portion 22 and the margins of the notch 23 are rounded as at 25 to avoid sharp corners at these points which might cause a tearing of the paper. The outer corners 26 of the portion 22 may also be rounded to prevent scratching the user's finger. The strip 20 constituting the holder is preferably made of a thin, stiff, scorch-resistant cardboard of a hardened character. It of course may be made of other suitable material but cardboard is probably the least expensive and easiest to handle in connection with a package of this type.

As heretofore mentioned, the end portion 21 of the strip 20 is adapted to be secured within the package and preferably underlies the various layers of the wrapping. In the preferred embodiment, the end portion 21 of the holder is adapted to be glued or otherwise secured to the inner surface of the liner 10 in such a position that the portion 22 may readily be bent to the position shown in Figs. 1 and 2. The portions 21 and 22 of the holder are integral because of being part of the same strip, but the portion 22 may be readily bent relative to the portion 21 by providing a hinge effect as by creasing the strip transversely thereof at the juncture between the portions 21 and 22. The portion 21 is thus held under the liner 10 when the package is opened so that the portion 22 is accessible and may be bent into its operative position as shown in Figs. 1 and 2. The position of the holder is also such that it is located outside of the area covered by the revenue stamp 17, since in opening the package the parts of the folded portions at one side of the revenue stamp are torn away to obtain access to the cigarettes within the package. With the holder located in this position, it is accessible for use when the package is opened.

When the package is made up, the end portion 22 is folded flat against the end of the cigarettes under the folded end portions 11, 12 and 13 of the liner. The package may be opened in the usual manner to gain access to the holder. While different people have different habits in connection with opening packages of cigarettes, one usual way is to first grasp the portion of the overlap 13 beyond the revenue stamp 17 and tear it along the edge of the revenue stamp to form a triangular portion 30, as shown in Fig. 5. Such triangular portion 30 may be torn off at that time or left in its open position as shown in that figure. The user then grasps the portion of the underlap 12 at the side of the revenue stamp 17 and tears it along the edge of the stamp to form a triangular portion 31. The portion 31 is then torn along

the edge of the package formed by the top and the face thereof and the tearing is continued along the edge formed by the top and the side of the package to remove the side portion of the side fold 11 and then the portion 30 is torn off, if it has not already been removed.

The portion 22 of the holder is thus exposed so that it may be bent through 180° to the position shown in Figs. 1 and 2 and fully expose the underlying cigarettes in the package. To be sure that the correct side portion of the top is opened to expose the holder, the words "Open Here" may be printed on the covering jacket 14 at the side of the package where the holder is placed, as shown in the drawing. Thus the user will be cautioned so that he will open that side of the top which will expose the holder.

In Fig. 6, I have shown another embodiment of the invention in which the holder is held in place by the outer or covering jacket 14 under the transparent sealing jacket constituting the outer layer of the ordinary wrapping for a package of cigarettes. Such a sealing jacket encloses the entire package and usually is provided with a tear strip 32 extending about the package adjacent the top thereof. The tear strip 32 is usually provided with a tab 33 by which it may be grasped to pull the strip around the package and effect the tearing action on the transparent material. In this manner the entire end portion of the transparent jacket is removed.

In the construction shown in this figure, the holder is of the same form as shown in Figs. 1 and 2 but its securing portion 21 is attached to either the inner surface or the outer surface of the covering jacket 14, as shown, and the portion 22 is folded over the top of the package and overlies the folded portion of the liner at one side of the revenue stamp 17 but underlies a portion of the folded end portion of the transparent jacket. Thus when the end portion of this jacket is removed by the action of the tear strip 32, the portion 22 of the holder is accessible and may be bent into operative position similar to that shown in Figs. 1 and 2. When the portion 22 is opened, the side parts of the folded portions of the liner 10 may be removed to open the package in the same manner as described in connection with Fig. 5. After use of the holder in this form of package, the portion 22 may be rebent into the position shown in Fig. 6 and will assist in retaining cigarettes within the package even though the side part of the folded portions of the liner have been removed.

I claim:

1. In a cigarette package containing a plurality of cigarettes, the combination of wrapper means enclosing said cigarettes and having end portions folded over the ends of the cigarettes, and a cigarette holder comprising a strip of relatively stiff sheet material having a preformed transverse bend for dividing the strip into a securing portion and a cigarette-holding portion, said securing portion being attached to said wrapper means at the interior thereof so as to constitute a normally inseparable part of the package with said cigarette-holding portion being folded inwardly of the package along said bend substantially perpendicularly to said securing portion and overlying the ends of the cigarettes under said folded end portions of the wrapper means, said cigarette-holding portion, upon opening of the wrapper means at said folded end portions, being foldable outwardly of the package along said bend through substantially 180° to its opposite substantially perpendicular position relative to said securing portion, and said cigarette-holding portion being provided with a notch for receiving and supporting a cigarette in said outwardly folded position.

2. The package of claim 1 further characterized in that said preformed transverse bend is substantially coincident with a corner fold of said wrapper means and said cigarette-holding portion is disposed at one side of an end of the package so as to be readily accessible upon normal opening of the package by tearing or removal of the

folded end portions of the wrapper means at said package end.

3. The package of claim 1 further characterized in that said wrapper means comprises at least two layers with said securing portion of said holder being permanently affixed to the innermost layer. 5

4. The package of claim 1 further characterized in that said wrapper means comprises an innermost wrapping surrounding said cigarettes and an outer jacket around said wrapping with said securing portion of said holder being permanently affixed to said jacket. 10
